(57) **CLAIM**

The ornamental design for a wheel disc for a vehicle, as shown and described.

DESCRIPTION

FIG. 1 is a front perspective view of a wheel disc for a vehicle according to our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a sectional view thereof, taken along line 9-9 in FIG. 3;

FIG. 10 is a sectional view thereof, taken along line 10-10 in FIG. 3;

FIG. 11 is a sectional perspective view thereof, taken along line 9-9 in FIG. 3; and,

FIG. 12 is a perspective view of the wheel disc for a vehicle shown in use.

The broken lines shown in FIG. 12 drawing are for the purpose of illustrating environmental structure and form no part of the claimed design. The hatch lines shown in FIGS. 9-11 are for the purpose of illustrating inside portions of the wheel disc for a vehicle and form no part of the claimed design.
